UNITED STATES PATENT OFFICE.

BRADFORD A. THOMAS, OF SAN FRANCISCO, CALIFORNIA, ASSIGNOR OF FIFTY-FIVE ONE-HUNDREDTHS TO MILTON AUERBACH AND FORTY-FIVE ONE-HUNDREDTHS TO FRANK J. SILVEY, BOTH OF SAN FRANCISCO, CALIFORNIA.

MONKEY-WRENCH.

1,114,415.

Specification of Letters Patent. Patented Oct. 20, 1914.

Application filed June 17, 1913. Serial No. 774,152.

To all whom it may concern:

Be it known that I, BRADFORD A. THOMAS, a citizen of the United States, residing at San Francisco, in the county of San Francisco and State of California, have invented certain new and useful Improvements in Monkey-Wrenches, of which the following is a specification, reference being had thereto in the accompanying drawing.

10 This invention relates to a wrench and the principal object of the invention is to provide the sliding jaw with an improved yoke, which yoke engages the worm screw by means of which the sliding jaw may be

15 moved.

Another object of the invention is to so form the yoke that it may be moved out of engagement with the worm screw.

Another object of the invention is to provide the yoke with an improved construction whereby it will be guided during its sliding movement.

With these and other objects in view, this invention consists of certain novel combinations, constructions, and arrangements of parts as will be hereinafter fully described and claimed.

This invention is illustrated in the accompanying drawing, wherein:—

30 Figure 1 is a side elevation of a wrench provided with the improved yoke. Fig. 2 is a view similar to Fig. 1 with the yoke shown in section and moved out of engagement with the worm screw. Fig. 3 is a perspective view of the yoke.

The wrench with which this improved yoke is connected is provided with the usual shank 10 at one end of which there is provided the stationary jaw 11; and the opposite end of which is provided with the handle 12. This handle is held in place by the nut 13 and is provided with the bearing 14 forming a support for one end of the worm screw 15.

45 The movable jaw 16 is of the usual type used in monkey wrenches and has its extension 17 provided with an opening through which the worm screw 15 passes. This opening through which the worm screw 15 passes is not threaded and therefore when the yoke is out of engagement with the worm screw, the movable jaw can then be quickly slid along the shank 10 from one position to another. The yoke

used in connection with this sliding jaw 16 comprises the side bars 18 which extend from the bridge 19 and have their end portions connected by the block 20, the inner face of which has leading from it the threaded pocket 21. This yoke is provided with 60 flanges 22 and 23 by means of which the yoke is slidably connected with the inner arms 24 of the movable jaw 16. These flanges 22 and 23 guide the yoke in its sliding movement and prevent the yoke from 65 becoming detached from the sliding yoke. It will also be noted that the flanges 23 come into engagement with the inner edges of the body portion 17, and thus form stops to limit the sliding movement of the yoke 70 in one direction. In order to yieldably hold the yoke in its normal position, there is provided a spring strip 25 which has one end secured to the movable jaw by means of the screws 26 and has its free portion engaging 75 the bridge 19 of the yoke. This spring normally holds the yoke in the position shown in Fig. 1, but permits the yoke to be moved to the position shown in Fig. 2 so that the block will be moved out of engagement with 80 the worm screw 15, and thus the movable jaw will be permitted to slide freely upon the worm screw.

In the operation of this wrench, the sliding jaw is first opened by moving the yoke 85 to the position shown in Fig. 2, and then sliding the movable jaw upon the shank 10. After the jaws are as far apart as is thought sufficient, the wrench is placed with the jaws 11 and 16 upon the opposite sides of the nut 90 which it is desired to turn, and the worm screw 15 is then rotated to bring the movable jaw into engagement with the nut. The movable yoke permits the sliding jaw to be quickly adjusted to a point thought to be 95 the right size and the worm screw can then be used for adjusting the sliding jaw to the desired position. By this construction, the wrench can be used with greater facility since it does not take very long to move 100 the movable jaw along the shank 10.

What is claimed is:—

A wrench comprising a shank having a fixed jaw, a sliding jaw positioned upon said shank, said sliding jaw provided with 105 inner arms, a yoke slidably upon said inner arms and adapted to move transversely across said shank, a worm screw engaging

said yoke, said worm screw adapted to move said slideable jaw, a plurality of flanges formed upon said slideable yoke and engaging said inner arms of said flanges terminating at a spaced distance from the rear portion of said yoke, a flat spring fixed to the inner end of said slideable jaw, said spring extending to pass within said yoke at its rear portion, said flanges terminating 10 to allow sufficient room for the passage of

said spring whereby said yoke will be normally held in engagement with said worm screw but may be moved from engagement therewith by compressing said flat spring.

In testimony whereof I hereunto affix my 15 signature in presence of two witnesses.

BRADFORD A. THOMAS.
